CLAIM

The ornamental design for a combined ground fault circuit interrupter receptacle with dual indicator lights, as shown and described.

DESCRIPTION

(62) Division of application No. 29/656,697, filed on Jul. 16, 2018, now Pat. No. Des. 917,398, which is a division of application No. 29/538,777, filed on Sep. 8, 2015, now Pat. No. Des. 826,861.

FIG. 1 is a side perspective view of a combined ground fault circuit interrupter receptacle with dual indicator lights showing our design;

(51) **LOC (13) Cl.** **13-03**

FIG. 2 is an opposing side perspective view thereof;

(52) **U.S. Cl.**

FIG. 3 is a front view thereof;

USPC **D13/137.1**

FIG. 4 is a side view thereof;

(58) **Field of Classification Search**

FIG. 5 is an opposing side view thereof;

USPC D13/137.1–137.8, 133, 139.1–139.4
CPC H01H 83/04

FIG. 6 is an environmental view thereof;

See application file for complete search history.

FIG. 7 is a side perspective view of another embodiment of a combined ground fault circuit interrupter receptacle with dual indicator lights showing our design;

D531,121 S 10/2006 Fort et al.
D536,305 S 2/2007 Fort et al.

FIG. 10 is a side view thereof;

FIG. 11 is an opposing side view thereof; and,

FIG. 12 is an environmental view thereof.

In the drawings, the broken lines are for the purpose of illustrating portions of the combined ground fault circuit interrupter receptacle with dual indicator lights that forms no part of the claimed design.
